GUN SIGHT

John D. Howell, Ilion, N. Y., assignor to Remington Arms Company, Inc., Bridgeport, Conn., a corporation of Delaware

Application February 29, 1944, Serial No. 524,355

9 Claims. (Cl. 33—58)

The present invention relates to a gun sight, and particularly an adjustable rear sight in which height adjustment for different ranges is accomplished by means of a longitudinally movable step member engaged as a support beneath the end of the leaf spring arm upon which the rear sight is carried. Because of slight variations between individual guns and the fact that a correct sight for one man may be incorrect for another, due to individual differences in shooting technique and in eye correlation in sighting the target along the sights, it is desirable that a simple and efficient means be provided for zeroing the sight at the correct height for the individual gun and its user, and it is an object of the present invention to provide an adjustment means of this character. A further object is to provide such zeroing adjustment means through which the step member may be raised or lowered through slight increments of movement without changing the normal angle of the range steps of the step member, to the end that the height adjustment in the zero or shortest range position of the sight will not change the relative elevation of the successive range steps with respect to each other, and consequently will not destroy the calculated correlation between the individual steps and pre-designated ranges.

It is proposed, according to the illustrated exemplary embodiment of the invention, to provide a longitudinally adjustable supporting cradle for the step member, adapted through relative longitudinal movement to lower or elevate the step member while maintaining it in exact parallel relation, and whereby the individual steps of the step member remain in the same angular relation to the axis of the gun, and represent the same increments of elevation, in any position of zeroing adjustment.

Another object is to provide a zeroing adjustment means which will effectually maintain its adjusted relation, while permitting convenient re-adjustment when desired and easy operation of the step member for normal range adjustment of the rear sight.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a side elevation of the rearward portion of a gun barrel, showing a rear sight assembly according to one embodiment of the inven-

tion, the adjustable step member being shown in its zero or shortest range position.

Fig. 2 is a plan view thereof.

Fig. 3 is a fragmentary longitudinal sectional view, on an enlarged scale, showing the step member in an intermediate position of range adjustment, the rear sight being elevated with respect to the zero position shown in Figs. 1 and 2.

Fig. 4 is a vertical transverse sectional view taken along the line 4—4 of Fig. 3.

Fig. 5 is a vertical transverse sectional view taken along the line 5—5 of Fig. 3.

Fig. 6 is a side elevation of the step member and its supporting cradle, according to a modified form of the invention.

Fig. 7 is a front end view of the cradle shown in Fig. 6.

Similar reference characters indicate corresponding parts throughout the several figures of the drawing.

Referring to the drawing, the gun barrel 10 is provided at its upper side with a dovetail mortise 11 in which the dovetail tenon 12 of the leaf spring arm 13 of the rear sight is engaged and secured, the rear sight being integrally formed upon the rear end of the arm 13, and consisting of an upwardly projecting rearwardly inclined flange 14 having its rearwardly facing observable surface 15 ground to a flat plane and provided centrally of its upper edge with an open sight notch 16. The leaf spring arm 13 is provided with a longitudinally extending slot 17 extending forwardly from the flange 14, and within which the adjustable step member is adapted to be slidably engaged, as will presently more fully appear, the lower edge of the flange 14 within the rearward end of the slot being ground at a rearwardly and downwardly inclined angle to provide a step engaging tooth edge 18. The upper side of the gun barrel 10 is provided with a longitudinally extending slot 19 centrally aligned with the slot 17, and in which the adjustable cradle and step members are slidably engaged and retained as a sub-assembly through the tension of the leaf spring arm 13, as will presently more fully appear.

The step adjustment means for the rear sight is in the form of a two-piece sub-assembly, comprising the step member engaged with the rear sight and a cradle member carrying the step member and engaged within the slot 19 of the gun barrel. It is to be understood, of course, that the cradle member can be carried directly on the barrel surface without a slot therein, the cradle and sight step being held in place by the leaf spring arm 13. The cradle member 20 is of U-

shape in cross section having a horizontal flat base portion provided at its rearward end with an upwardly and rearwardly inclined ramp 21 and adjacent its forward end with a transversely disposed knife edge support 22, formed by lancing out a pair of support portions 23 from the opposed side walls of the cradle and bending these portions inwardly and then vertically in contact with each other, as shown clearly in Fig. 5. The side walls of the cradle member are projected upwardly above the ramp 21 and above the knife edge 22, as at 24 and 25, and are bent inwardly toward each other at a slight angle for the purpose of frictionally retaining the relatively adjusted position of the step member within the cradle member, as will presently more fully appear. Between the upwardly extending side wall portions 24 and 25 the upper edges of the side walls are arched downwardly, as at 26, to substantially clear the step formation in the upper side of the step member.

The step member 27 is of substantially the same length as the cradle member, and is provided at the rearward end of its under surface with a bearing foot portion 28, disposed at a corresponding angle to the ramp 21 and slideably engaged thereon. At the forward end of its under surface, the step member is provided with a series of relatively small teeth or serrations 29, disposed along an inclined plane parallel to the inclined plane of the foot portion 28 and the ramp 21, and of a length substantially corresponding to the length of the ramp. These serrations are engaged by the knife edge 22 at substantially the same point intermediate their ends as the point of engagement of the foot portion 28 intermediate the ends of the ramp 21, the height of the knife edge being so calculated that it supports the step member in parallel relation to the cradle member in any position of longitudinal adjustment of the cradle member relatively to the step member. The knife edge 22 is in the form of an inverted V, having an angle shown for example as approximately 45° at each side of the vertical plane of the knife edge, and the tooth formations 29 are at the same angle so that, through their disposition in an inclined plane, these tooth formations face forwardly and thus resist relative rearward movement of the cradle member relatively to the step member, this being the normal ratcheting direction of adjustment of the step member relatively to the rear sight.

The step member is provided in its upper surface with a series of height adjusting step formations 30 of gradually increasing height forwardly, and which are engaged by the tooth 18 of the rear sight so that by forward adjustment of the step the open sight notch of the rear sight is adjusted for predesignated ranges, the rearward or lowest step formation being the zero point representing the shortest range. The cradle member and the step member constitute a sub-assembly disposed in cooperative relation in the slot 19 of the gun barrel and in the slot 17 of the leaf spring arm 13 of the rear sight, this sub-assembly normally operating as a unit for range adjustment through the frictional retention of one with respect to the other by means of the inwardly bent gripping sides of the cradle member and the interlocking engagement of the knife edge with the teeth 29. As these teeth are in opposite direction to the direction of the steps 30 the sub-assembly may be range adjusted rearwardly as a unit through ratcheting engagement with the rear sight, without changing the zeroing adjustment, forward

range adjustment being carried out by lifting the rear sight out of engagement with the step member.

In operation the rear sight is set at the zero adjustment, as shown in Figs. 1 and 2, and thereupon the cradle member is longitudinally adjusted with respect to the step member to bring the step member to the desired zeroing height for the individual gun and its user. In any position of height adjustment the step member remains in parallel relation to the cradle member, so that there is no change in the relation between the height increments of the steps for predesignated ranges. After such zeroing adjustment the sub-assembly, constituted by the cradle member and the step member, is operated as a unit in the normal manner of the usual adjustable step, Fig. 3 illustrating one range adjustment of the sub-assembly with respect to the zero position as shown in Figs. 1 and 2.

In Figs. 6 and 7 there is illustrated a modified form of cradle member in which the knife edge 22 is formed by bending upwardly and rearwardly a lanced out portion 31 at the forward end of the base of the cradle member, this portion being at a 45° angle and its end being ground to a transverse flat face 32 at right angles thereto, so that this end face constitutes with the inclined surface of the portion 31 a 90° knife edge. Its co-operation with the step member is substantially identical with the embodiment of the invention shown in Figs. 1 to 5.

The form of the invention illustrated in the drawing and described herein is typical and illustrative only, and it is evident that the invention is capable of embodiments in other forms.

What is claimed is:

1. In a gun sight for attachment to a gun barrel, a height adjustable sight member supportable upon the barrel longitudinally of its axis, a longitudinally movable range adjustment member engageable with said sight member to raise and lower it, a longitudinally movable height adjusting member, and a pair of longitudinally spaced correspondingly inclined ramp means cooperating between said height adjusting member and said range adjustment member to height adjust said range adjustment member uniformly along its length whereby a given angular relation to the axis of the gun barrel is maintained in any position of height adjustment of said range adjustment member.

2. In a gun sight for attachment to a gun barrel, a height adjustable sight member supportable upon the barrel longitudinally of its axis, a longitudinally movable range adjustment member engageable with said sight member to raise and lower it, a longitudinally movable height adjusting member, and a pair of longitudinally spaced correspondingly inclined ramp means cooperating between said height adjusting member and said range adjustment member to height adjust said range adjustment member uniformly along its length whereby a given angular relation to the axis of the gun barrel is maintained in any position of height adjustment of said range adjustment member, at least one of said ramp means comprising a series of tooth serrations on one of said members and a knife edge on the other of said members.

3. In a gun sight for attachment to a gun barrel, a height adjustable sight member supportable upon the barrel longitudinally of its axis, a longitudinally movable range adjustment member engageable with said sight member to raise and

lower it, a longitudinally movable height adjusting member, and a pair of longitudinally spaced correspondingly inclined ramp means cooperating between said height adjusting member and said range adjustment member to height adjust said range adjustment member uniformly along its length whereby a given angular relation to the axis of the gun barrel is maintained in any position of height adjustment of said range adjustment member, one of said ramp means comprising a series of serrations on one of said members and a knife edge on the other of said members, and the other of said ramp means comprising a bearing foot on said one member and an inclined surface on said other member.

4. In a gun sight for attachment to a gun barrel, a height adjustable sight member supportable upon the barrel longitudinally of its axis, a longitudinally movable range adjustment member engageable with said sight member to raise and lower it, a longitudinally movable height adjusting member, and a pair of longitudinally spaced correspondingly inclined ramp means cooperating between said height adjusting member and said range adjustment member to height adjust said range adjustment member uniformly along its length whereby a given angular relation to the axis of the gun barrel is maintained in any position of height adjustment of said range adjustment member, one of said ramp means comprising a series of serrations on said range adjustment member and a knife edge on said height adjusting member, and the other of said ramp means comprising a bearing foot on said range adjusting member and an inclined surface on said height adjusting member.

5. In a gun sight for attachment to a gun barrel, a height adjustable leaf spring sight member supportable upon the barrel longitudinally of its axis, and having a longitudinal slot, a longitudinally movable range adjustment step member engageable in said slot adapted through longitudinal movement to raise and lower said sight member, a cradle member carrying said step member and longitudinally adjustable relatively thereto, and ramp means cooperating between said cradle and step members adapted to height adjust said step member, whereby a given angular relation to the gun barrel is maintained in any position of height adjustment of said step member.

6. In a gun sight for attachment to a gun barrel, a height adjustable leaf spring sight member supportable upon the barrel longitudinally of its axis, and having a longitudinal slot, a longitudinally movable range adjustment step member engageable in said slot adapted through longitudinal movement to raise and lower said sight member, a cradle member carrying said step member and longitudinally adjustable relatively thereto, and comprising a base and upwardly extending side walls clamping engaged with the sides of said step member to frictionally retain said cradle and step members against relative longitudinal movement, and ramp means cooperating between said cradle and step members adapted to height adjust said step member, whereby a given angular

relation to the gun barrel is maintained in any position of height adjustment of said step member.

7. In a gun sight for attachment to a gun barrel, a height adjustable leaf spring sight member supportable upon the barrel longitudinally of its axis, and having a longitudinal slot, a longitudinally movable range adjustment step member engageable in said slot adapted through longitudinal movement to raise and lower said sight member, a cradle member carrying said step member and longitudinally adjustable relatively thereto, and comprising a base and side walls, and ramp means cooperating between said cradle and step members adapted to height adjust said step member, whereby a given angular relation to the gun barrel is maintained in any position of height adjustment of said step member, said ramp means including a series of tooth serrations on the under side of said step member and a knife edge on said cradle member interlockingly engaged with said tooth serrations.

8. In a gun sight for attachment to a gun barrel, a height adjustable leaf spring sight member supportable upon the barrel longitudinally of its axis, and having a longitudinal slot, a longitudinally movable range adjustment step member engageable in said slot adapted through longitudinal movement to raise and lower said sight member, a cradle member carrying said step member and longitudinally adjustable relatively thereto, and comprising a base and side walls, and ramp means cooperating between said cradle and step members adapted to height adjust said step member, whereby a given angular relation to the gun barrel is maintained in any position of height adjustment of said step member, said ramp means including a series of tooth serrations on the under side of said step member and a knife edge on said cradle member interlockingly engaged with said tooth serrations, said knife edge consisting of a pair of pointed support portions extended inwardly from said side walls.

9. In a gun sight for attachment to a gun barrel, a height adjustable leaf spring sight member supportable upon the barrel longitudinally of its axis, and having a longitudinal slot, a longitudinally movable range adjustment step member engageable in said slot adapted through longitudinal movement to raise and lower said sight member, a cradle member carrying said step member and longitudinally adjustable relatively thereto, and comprising a base and side walls, and ramp means cooperating between said cradle and step members adapted to height adjust said step member, whereby a given angular relation to the gun barrel is maintained in any position of height adjustment of said step member, said ramp means including a series of tooth serrations on the under side of said step member and a knife edge on said cradle member interlockingly engaged with said tooth serrations, said knife edge consisting of an extension of said base inclined upwardly therefrom.

JOHN D. HOWELL.
